EDGAR J. MASKERY, OF PATERSON, NEW JERSEY

CRATE FOR USE IN WEIGHTING FABRICS

Application filed April 15, 1929. Serial No. 355,130.

In weighting piece goods the practice has been for the workmen to pass the piece progressively by hand into the weighting vat from the container in which it is brought thereto until its whole length was introduced, which operation required a certain amount of care in handling the goods to prevent their being rubbed, especially if they were of silk or other delicate texture, and a considerable 10 waste of time if, as usual, the piece was of considerable length. To avoid this it has been proposed to place the piece or pieces in a container formed like a box having a perforated bottom and deposit the thus loaded box in the 15 vat, in which case there was the fault that where the open sides of folds or creases in the goods were presented to the sides of the box a sufficient seal would frequently be formed to prevent the weighting liquid from 20 reaching within the folds or at least from impregnating the goods within such folds or as much as elsewhere, with the result that when the goods were later dyed there would be streaking or other blemishing thereof.

25 The object of this invention is to provide a crate-like receptacle in which the goods may be placed and brought to the vat and which may be then hung in the vat so that the goods are submerged in the weighting liquid, and 30 also to construct such crate so that it will be proof against the chemical action of the liquor.

In the accompanying drawing,

35 Fig. 1 is a perspective view of the improved crate and also shows in dotted outline two rods by which it may be supported when hung within the vat;

Fig. 2 is a plan of a blank from which the bottom of a crate is formed;

40 Fig. 3 is an end elevation of one of the hanger-forming straps by which the crate is suspended from the mentioned rods;

Fig. 4 is a sectional view of the weighting vat, showing the crate hung therein; and

45 Fig. 5 is a transverse fragmentary sectional view of the crate.

To form the bottom a of the crate I provide a substantially oblong blank such as is shown in Fig. 2 having extensions at its several 50 edges, and these are bent up 90 degrees to

form upstanding flanges a' on the bottom a . This bottom and its flanges are provided with numerous perforations a^2 ; this foraminous form of the bottom permits all weighting liquor to drain away when the crate is removed from the vat. At each of the four corners of the bottom the ends of adjoining flanges meet or nearly meet each other.

55 At each corner of the bottom is an upright d . This is formed of an elongated rectangular strip bent on a longitudinal median line into right angular form. The two leaves or walls of each of such uprights d are riveted to the ends of the flanges a' at a corner of the bottom, said ends being within the angle 60 of the upright.

65 At or near the tops of the uprights, which are all the same height, there are riveted thereto, as at x , the ends of the longitudinal or side bars b and the ends of the transverse or end bars c ; the ends of the bars b and c also are within the angles of the upright d .

70 To support the crate in the box there are the two pairs of hangers e . It is preferable to 75 form each pair of hangers of a single strap which at points about equal to the width of the bottom a and equidistant from the ends of the strap has its end portions bent up at right angles in the same direction. These 80 straps are assembled with the crate in the manner shown in Fig. 1 so that the mid-portion of each underlies its bottom and its two end portions upstand, the two straps being 85 arranged equidistant from the respective ends of the crate across which their mid-portions extend transversely. The straps are secured to the side bars b and bottom flanges a' by other rivets x . The upper ends of the straps are twisted 90 degrees and their extremities 90 rebent in the form of hooks e' , and by the suspending means thus formed the crate, resting on rods f , in turn resting on the sides of the vat y , may be suspended in the weighting liquor in said vat as shown in Fig. 4.

95 All of the parts of the crate are constructed of metal so as to have the necessary strength and durability, since the weight of the goods carried thereby, especially when wet, is considerable. As the weighting liquor would act 100

to corrode the metal and the product of the corrosion would produce a blemish on the goods where the latter contact therewith I coat all the parts of the crate (excepting possibly the upper extremities of the hangers *e*) with rubber or other non-corrodible substance; this is illustrated in Fig. 5 at *z*.

In the use of the improved crate there is the advantage that the whole mass of goods can be deposited in the weighting liquor in a single operation and that, while the goods are kept in place on the bottom by the corner uprights, the side and end bars and the hangers, there is no opportunity for pockets or folds to be formed in the goods where they contact with any part of the crate so that the liquor is prevented free access thereto.

Having thus fully described my invention, what I claim is:

- 23 1. A crate for use in weighting fabrics comprising a foraminous substantially rectangular bottom, uprights extending up from and rigidly secured to the bottom, bars spaced from and above the bottom and rigidly secured to and connecting the uprights, and hangers extending upwardly from and secured to the bottom at opposite sides thereof and having suspending means above the bars.
- 30 2. A crate for use in weighting fabrics comprising a foraminous substantially rectangular bottom, uprights extending up from and rigidly secured to the bottom, each upright being angular in horizontal section and receiving a corner of the bottom in its interior angle, bars secured to and connecting the uprights, the adjoining ends of each two adjoining bars being received within the interior angle of the corresponding upright, and hangers extending upwardly from and secured to the bottom at opposite sides thereof and having suspending means above the bars.
- 35 3. A crate for use in weighting fabrics comprising a foraminous substantially rectangular bottom, uprights extending up from and rigidly secured to the bottom, bars spaced from and above the bottom and rigidly secured to and connecting the uprights, and U-shaped straps extending under and secured to the bottom and having their ends reaching and also provided with suspending means above the bars.
- 45 4. A crate for use in weighting fabrics comprising a foraminous substantially rectangular bottom, uprights extending up from and rigidly secured to the bottom, bars spaced from and above the bottom and rigidly secured to and connecting the uprights, and hangers extending upwardly from and secured to the bottom at opposite sides thereof and having suspending means above the bars, said bottom, uprights, bars and hangers being coated with a non-corrodible substance.

In testimony whereof I affix my signature.

65 EDGAR J. MASKERY.
